UNITED STATES PATENT OFFICE.

GILBERT M. WILLIAMS, OF MAYSVILLE, KENTUCKY, ASSIGNOR OF ONE-HALF TO DE WITT C. FRANKLIN, OF MAYSVILLE, KENTUCKY.

DENTAL FINGER-GUARD.

SPECIFICATION forming part of Letters Patent No. 689,940, dated December 31, 1901.

Application filed April 20, 1901. Serial No. 56,775. (No model.)

To all whom it may concern:

Be it known that I, GILBERT M. WILLIAMS, a citizen of the United States, residing at Maysville, in the county of Mason and State of Kentucky, have invented a new and useful Dental Finger-Guard, of which the following is a specification.

This invention relates to dental appliances, and has for its object to provide means for the protection of the fingers of an operator when polishing a filling in the tooth of a patient with an ordinary polishing or abrading strip commonly held in the hand and pressed against the filling by the forefinger or thumb. It is furthermore designed to provide such means in the form of a finger-clip constructed to be readily slipped upon the tip of the finger, so as to protect the same from abrasion by contact with a rough tooth or filling, and also constructed to hold the polishing-strip and prevent the latter from slipping from the finger and cutting the gums of the patient.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view showing the application of the present device. Fig. 2 is a perspective view looking at the front side of the dental-finger protector. Fig. 3 is a rear elevation thereof. Fig. 4 is a front elevation. Fig. 5 is a detail perspective view of a modified form of the device. Fig. 6 is a rear elevation thereof.

Like characters of reference designate corresponding parts in all of the figures of the drawings.

In carrying out the present invention there is provided a substantially semitubular piece of sheet spring metal to form the body 1 of the device, the rear edge thereof being rounded or convex, as at 2, while one corner of the front edge has a portion cut therefrom,

so as to produce a terminal forwardly-directed projection which conforms to the general tubular shape of the finger-piece and is tapered outwardly, the outer extremity thereof being bent back upon the outer convex side thereof to form an overhanging lip or ear 4, which is spaced slightly from the projection. At the opposite rear corners of the part 1 the latter is extended laterally outward in opposite directions and bowed around across the concaved inner side of the body, so as to form the outwardly-tapered and reduced spring-clips 5, which are designed to elastically embrace the back of the finger or thumb to which the guard may be applied, whereby the front of the guard covers the front of the finger-tip. At the base of what will be termed the "upper edge" of the projection 3, as shown in Fig. 2, there is formed a slight notch 6, and the portion of the guard which is cut out to form the notch is bent over across the projection, so as to form an overhanging lip or ear 7, arranged opposite and also reversely with respect to the terminal lip 4 and designed to coöperate therewith and form a seat for the reception of the ordinary polishing or abrading strip 8. (Shown in Fig. 1.) This strip is slid endwise across the front of the guard from the rear end thereof and between the opposite lips 4 and 7, which snugly embrace the opposite edges of the strip, and thereby hold the same flat against the front of the guard, and thereby prevent the strip from slipping from the finger and cutting the gums of the patient when polishing a rough filling. The metallic guard also forms a firm backing for the polishing-strip and likewise protects the finger of the operator from injury upon any rough portions of teeth and fillings.

In Figs. 5 and 6 there has been shown a modified form of the device, in which the rear lip 7 has been omitted, the guard being otherwise the same as hereinbefore described. In this latter form of the device it requires two hands to perform the polishing operation, as the single lip merely prevents lateral displacement of the polishing-strip in one direction, the other hand of the operator being used to hold the free end of the strip, so as to prevent displacement thereof, whereby the

latter form of the device is essentially a guard to prevent injury to the finger rather than a holder for the polishing-strip.

What is claimed is—

- 5 1. A combined dental finger-guard and polishing-strip holder constructed for detachable application to the tip of a finger, and having means for holding a polishing-strip across the outer or front side of the guard.
- 10 2. A dental finger-guard for use in polishing teeth and fillings, consisting of a guard-plate which is constructed to fit the inner side of the tip of a finger, and having opposite spring-clips constructed to embrace the back 15 of the finger to which the guard is applied.
- 15 3. A dental finger-guard, consisting of a plate which is bowed to fit the inner side of the tip of a finger, and has a forwardly-directed projection at one longitudinal edge thereof, 20 and opposite spring-clips extending from the opposite rear corners of the plate and bowing across the back thereof.
- 25 4. A dental finger-guard constructed for application to the front or inner side of the tip of a finger, and having a lip overhanging one edge thereof and constructed to embrace an edge of a polishing-strip to hold the latter to the guard.
- 30 5. A dental finger-guard and polishing-strip holder consisting of a guard-plate constructed for application to the inner side of the tip of a finger, and having a longitudinal forwardly-directed projection at one edge thereof, the outer terminal of the projection being bent 35 over across the outer side thereof to form an overhanging lip constructed to embrace one edge of a polishing-strip and hold the same to the guard.
- 35 6. A dental finger-guard and polishing-strip holder consisting of a guard-plate constructed

for application to the inner side of the tip of a finger, and having a longitudinal projection directed forwardly at one edge thereof, the outer terminal of the projection being bent over across the outer side thereof to 45 form an overhanging lip, and there being a notch formed at the rear end of one edge of the projection, the material cut out by the notch being bent over across the projection to form an overhanging lip arranged opposite 50 and reversely with respect to the outer terminal lip.

7. A dental finger-guard and polishing-strip holder formed from a single blank of metal, which is bowed laterally to fit the inner side 55 of the tip of a finger, there being a portion of the plate projected forwardly at one edge thereof and tapered outwardly, said projection conforming to the general lateral bow of the plate and also being bowed longitudinally, 60 the outer terminal of the projection being bent over across the outer convex side thereof to form an overhanging lip, the base portion of one edge of the projection being notched and the portion cut out thereby being bent 65 over across the projection to form an overhanging lip arranged opposite and reversely with respect to the outer terminal lip, and the opposite rear corners of the plate being extended in opposite directions and bowed 70 across the inner concave side of the plate to form spring finger-embracing clips.

In testimony that I claim the foregoing as my own I have hereto affixed my signature in the presence of two witnesses.

GILBERT M. WILLIAMS.
